US00D926062S

(12) **United States Design Patent** (10) Patent No.: **US D926,062 S**
(45) Date of Patent: **** Jul. 27, 2021**

(54) **WIRELESS BUTTON FOR FAST RESPONSE**

(71) Applicant: **AJAX SYSTEMS CYPRUS HOLDINGS LTD**, Nicosia (CY)

(72) Inventors: **Oleksandr Konotopskyi**, Kyiv (UA);
Ilshat Garipov, Haapsalu (EE)

(**) Term: **15 Years**

(21) Appl. No.: **35/509,042**

(22) Filed: **Aug. 5, 2019**

(80) **Hague Agreement Data**

Int. Filing Date: **Aug. 5, 2019**

Int. Reg. No.: **DM/206935**

Int. Reg. Date: **Aug. 5, 2019**

Int. Reg. Pub. Date: **Apr. 10, 2020**

(51) **LOC (13) Cl. 10-05**

(52) **U.S. Cl.**

USPC **D10/104.1**

(58) **Field of Classification Search**

USPC D10/104.1, 104.2; D13/171, 158

See application file for complete search history.
